UNITED STATES PATENT OFFICE.

ROBERT ABBOTT HADFIELD, OF WESTMINSTER, AND ALEXANDER GEORGE McKENZIE JACK, OF SHEFFIELD, ENGLAND.

MANUFACTURE OF STEEL INGOTS.

1,323,628.

Specification of Letters Patent. Patented Dec. 2, 1919.

Application filed July 14, 1917. Serial No. 180,603.

To all whom it may concern:

Be it known that we, Sir ROBERT ABBOTT HADFIELD, baronet, F. R. S., and ALEXANDER GEORGE McKENZIE JACK, subjects of the 5 King of Great Britain and Ireland, residing, respectively, at Westminster, England, and Sheffield, in the county of York, England, have invented Improvements in or Relating to the Manufacture of Steel Ingots, 10 of which the following is a specification.

In the manufacture of ingots of steel or other extrusable metal, and especially of such ingots which are to be subjected to the process of extrusion, it has heretofore been 15 usual to cast steel and other ingots of taper shape in order that they may more readily be removed from their molds, the smaller ends being either at the top or at the bottom. When however such a taper ingot is 20 placed in a matrix arranged in either a vertical or a horizontal position, and especially the latter, preparatory to being subjected to an extrusion process, as for example for producing hollow articles therefrom, the 25 small end of the ingot, owing to its having no centering means, may not be arranged centrally within the matrix but is usually nearer to one side of the die than the other, and, in the case of a matrix arranged horizontally, 30 rests on the lower side in the matrix, with the result that upon forcing an extruding bar or plunger vertically or horizontally into the ingot, the hole thus formed in the latter is not disposed centrally 35 throughout the ingot but on the contrary is generally eccentric thereto except at the end first formed by the bar or plunger so that the metal is not disposed symmetrically around the hole throughout its entire length. 40 Now the present invention has for object to obviate the disadvantage above referred to and while producing an ingot of gradually decreasing cross sectional area along its length, so as in effect to be of taper shape, 45 to yet provide a gradually increasing cooling surface, preferably from top to bottom, to insure the proper cooling of the ingot after being cast, as well as means for centering the ingot in an extrusion die. 50 For this purpose, according to the invention, a steel or other metal ingot of taper shape is cast with a longitudinally grooved or fluted surface, the grooves or flutes be-

ing of concave shape as seen in cross section or plan, and of gradually increasing 55 depth in a transverse direction from points at or toward the upper end of the ingot to the lower end thereof while the outer edges of the longitudinal ribs between the grooves or flutes are parallel, or nearly so, to the 60 longitudinal axis of the ingot and are preferably of convex shape in cross section, the molds in which the ingots are cast being of course suitably shaped internally to cause 65 this formation to be imparted to the ingots. 70

Ingots according to the invention may be circular, square, rectangular or polygonal in general or overall shape as seen in end view or plan, as may be desired, and in the case of an ingot which is circular in section at its upper end the grooves or flutes may be somewhat closely pitched so that in a steel ingot of ordinary size, say of about 75 twelve inches in diameter or width, there will be several grooves or flutes, say for example six to twelve.

In the accompanying illustrative drawings Figure 1 is a side elevation and Fig. 2 an end view of the base, of a grooved or fluted steel ingot constructed according to 80 the invention, the upper end portion of the ingot being circular in section. Figs. 3, 4, 5, 6, 7 and 8 are cross sections on the lines A A, B B, C C, D D, E E and F F respectively of Fig. 1. Figs. 9 and 10 are similar 85 views to Figs. 1 and 2 respectively, and Fig. 11 a cross section on the line G G of Fig. 9 showing a grooved or fluted steel ingot of hexagonal shape while Fig. 12 shows in plan view, an ingot of square shape. 90

In the example shown in Figs. 1 to 8 inclusive, the ingot is circular in general or overall shape as seen in plan, a being the grooves or flutes of concave shape in cross section extending from an upper cylindrical portion b to the bottom of the ingot. c is the ordinary discard portion or feeding head of the ingot which is cut off before the ingot is converted into the desired article by extrusion or otherwise. The diameter 95 of the ingot is slightly greater at the portion b than at the base to facilitate withdrawal from the casting mold, and the grooves or flutes a are of gradually increasing depth in an inward or transverse direction 100 from their upper to their lower ends, 105

the outer edges of the longitudinal ribs d , shown as of convex shape, between the grooves or flutes, being parallel or nearly so, as above indicated, and included in the term 5 substantially parallel, to the longitudinal axis of the ingot.

In Figs. 9, 10 and 11 the ingot is of polygonal shape throughout its length, being shown as of hexagonal shape, each side 10 being grooved or fluted as described.

In Fig. 12 the ingot is square at the top except that the corners are rounded, the contiguous grooves or flutes gradually getting deeper in the transverse direction as they 15 proceed toward the lower end of the ingot as in the other examples.

In each case the measurements across the outer rounded edges of the ribs d are the same, or practically so, from end to end of 20 the ingot, except for the slight extent required to facilitate removal of the ingot from its casting mold as indicated above, that is to say, the measurements are substantially the same.

25 The lower end of the ingot may be of rounded shape as shown in Fig. 1, or of flat shape as shown in Fig. 9. For some purposes it is preferably made of rounded shape.

30 By constructing ingots in the manner described, it will be seen that in the case of an ingot the sectional area of which is greatest at its upper end, as in the example shown in Figs. 1 to 8 inclusive, which is the 35 form preferred, the external cooling surface of the ingot will be of gradually increasing area in a downward direction whereas the cross sectional area of the ingot will be gradually decreasing from or near 40 the top to the bottom of the ingot so that after being cast, the ingot will cool most rapidly at the bottom, not only by reason of the greater cooling surface, but also by reason of the conduction away of heat due 45 to the edges of the ribs d being in contact with the mold and to the flutes generally, the rate of cooling decreasing upwardly as in an ingot which is cast with its largest section at its upper end. By this means, as 50 the molten metal gradually cools and solidifies from the lower end of the ingot upward, the molten metal above is able to descend and compensate for contraction on cooling and prevent piping throughout the entire 55 length of the ingot so that the whole of the ingot, after removal of the discard portion c is available for use. Furthermore, such an ingot when placed in a matrix preparatory to being subjected to an extruding 60 process to form a hollow body, will be centered truly within the matrix by means of the outer edges of its longitudinal ribs d acting as centering means so that the metal surrounding the hole when formed in the 65 ingot will be disposed symmetrically and

concentrically around such hole and all parts of its sectional area will have been subjected substantially to the same pressure, the flutes or grooves being gradually and equally filled up or eliminated by expansion 70 as the metal is extruded.

It will be observed that the uniform arrangement of the numerous grooves and the comparatively narrow intervening ribs enables the ingot to be used with marked effect 75 in carrying out the extrusion method in which the ingot is first punched centrally and then subjected to the action of mandrels or a succession of mandrels to produce, for example, gun-tubes, howitzers, etc. 80 The longitudinal grooves are of substantially uniform width from end to end but of varying depth and they constitute arcs of closely approximated intersecting circles. For example, in Fig. 3 the circles indicated by the 85 arcs would be approximated; in Fig. 4 the circles would touch each other; while in the succeeding figures the circles would intersect; and so on until finally they would merge in Fig. 8. The ribs are, of course, comparatively narrow until they finally disappear in Fig. 8 in the plain cylindrical part b of the ingot. These intervening ribs have substantially the same circumference as the cylindrical part, b , and gradually decrease in width 90 from one end to the other of the ingot. This uniform treatment of the surface by the formation of the concave grooves illustrated and described secures the best results when using the ingot to form a gun tube, for example. The metal under radial pressure fills out the concave grooves until the whole tube is substantially of the same formation from end to end and of substantially the same density, the effect of the radial pressure being progressively greater as it proceeds from the top to the bottom of the ingot. 100

105 In the form illustrated in Figs. 1-11 the gun tube is substantially completed by the 110 action of the mandrels alone upon the ingot thus grooved. Therefore by the described uniform relation of the grooves a great economy is secured, especially when the ingot is used for the formation of gun 115 tubes, howitzers, etc.

120 For the purpose of insuring complete concentricity of the extruded ingot, the measurement of the ingot across the ribs may be slightly in excess of the internal diameter of the extruding die so that the ingot may require to be subjected to a slight end pressure in order to bring it into position in the matrix for extrusion.

125 In brief, stated in other words, there is provided a cast ingot wherein the cross sectional area is variable and the diameter constant substantially for the length thereof; and that the cast pyramidal ingot has means for maintaining its longitudinal axis concen- 130

tric with a matrix for a forging operation.

With reference to the grooves it may be stated in illustrative terms that they gradually fade away toward one end of the ingot.

In mathematical terms it may be said that the cross sectional area and the perimeter of that area vary between the limits

10

$$\frac{\pi r^2}{2\pi r}$$

and

$$\frac{\pi r^2}{n(2\pi r)},$$

15 where "n" represents any value greater than 1.

What we claim is:—

1. A metal ingot having a longitudinally grooved surface formed by grooves of varying transverse depth along their length, the outer edges of the ribs between the grooves being substantially parallel to the axis of the ingot.

2. A metal ingot having in its peripheral surface longitudinal grooves of varying depth along their length with the outer edges of the ribs between the grooves of convex shape and substantially parallel to the longitudinal axis of the ingot.

3. A metal ingot of substantially uniform overall dimensions along its length and having a longitudinally grooved peripheral surface, the grooves being of varying transverse depth along their length and of concave shape in cross section.

4. A metal ingot of substantially uniform overall dimensions along its length and having longitudinal peripheral grooves of concave shape and of varying transverse depth along their length, the ribs between such grooves having rounded edges.

5. A metal ingot of tapering cross sectional area, having in its peripheral surface longitudinal grooves of concave shape with the edges of the ribs between the grooves substantially parallel to the axis of the ingot.

6. A metal ingot having a rounded lower end and longitudinal grooves of varying transverse depth along their length and extending from its lower end portion upward, the transverse depth being greatest at the lower ends of the grooves and the edges of the ribs between the grooves being substantially parallel to the axis of the ingot.

7. A metal ingot provided for part of its length with longitudinal grooves of varying transverse depth from their lower ends upward, the edges of the ribs between the grooves being substantially parallel to the axis of the ingot.

8. A metal ingot provided for part of its length with longitudinal grooves of concave section and of gradually decreasing trans-

verse depth from their lower ends upward, the remaining portion of the ingot being of substantially uniform cross section and the ribs between the grooves having their edges substantially parallel to the axis of the ingot and flush with the ungrooved portion of the ingot.

9. A metal ingot provided for part of its length with longitudinal grooves of concave section and of gradually decreasing transverse depth from their lower ends upward, the remaining portion of the ingot being of substantially cylindrical shape and the narrow ribs between the grooves having their edges substantially parallel to the axis of the ingot and flush with the surface of the cylindrical portion of the ingot.

10. A metal ingot having a rounded lower end and a substantially cylindrical upper end portion, the intermediate portion being formed with longitudinal grooves of concave section and of gradually decreasing transverse depth from their lower ends upward and the ribs between the grooves having rounded outer edges substantially parallel to the axis of the ingot and flush with the surface of the cylindrical portion of the ingot.

11. A metal ingot having a portion of its longitudinal surface of cylindrical shape and the remainder and greater portion of its length of longitudinally grooved shape, the latter portion being of waved shape circumferentially with the concave grooves of greater width than the intermediate ribs or ridges and of varying transverse depth along their length, the ribs or ridges having their peripheral edges or surfaces substantially parallel to the axis of the ridge.

12. A metal ingot having a polyhedral longitudinally grooved surface formed of alternating longitudinally extending grooves of concave shape in cross section and intervening ribs of convex shape in cross section, the grooves being of varying transverse depth along their length and of greater width than the ribs, and the outer edges of the ribs being substantially parallel to the longitudinal axis of the ingot.

13. A metal ingot having a longitudinally grooved surface formed by grooves of varying transverse depth along their length, the outer edges of the narrow ribs between the grooves being substantially parallel to the longitudinal axis of the ingot and the ribs so formed being substantially triangular in cross section and having concaved sides thereby to be of the minimum cross-sectional area adapted to permit of the uniform radial extension of the metal.

14. A cast ingot wherein the cross-sectional area is variable and the diameter constant substantially for the length thereof.

15. A cast pyramidal ingot having means

for maintaining its longitudinal axis concentric with a matrix for a forging operation.

16. A cast ingot wherein the relation between the cross-section area and the perimeter of that area vary between the limits

$$10 \quad \frac{\pi r^2}{2\pi r} \quad \frac{\pi r^2}{n(2\pi r)},$$

where "n" represents any value greater than 1.

15 17. A metal ingot having longitudinal grooves, the grooves being of substantially uniform width from end to end but of varying depth.

18. A metal ingot having longitudinal grooves constituting arcs of closely approximated or intersecting circles, each groove of substantially uniform width from end to end but of varying depth.

19. A metal ingot adapted to fit the bore 25 of a matrix and having longitudinal grooves of varying width from end to end forming

a major part of its surface with comparatively narrow intervening ribs which fit the bore of the matrix so that the ingot may lie in the bore of the matrix with its axis concentric with that of the matrix, and so that under the radial pressure of a mandrel the metal is forced into contact with the walls of the bore of the matrix.

20. A metal ingot having a cylindrical part adapted to fit the bore of a cylindrical matrix and having longitudinal grooves proceeding from the opposite end of the ingot and fading away into the cylindrical part, the ribs between the grooves fitting 40 the bore of the matrix, so that the ingot may lie in the bore of the matrix with its axis concentric with that of the matrix.

Signed at 22 Carlton House Terrace, Westminister, London, England, this sixth 45 day of June, 1917.
